Patented Mar. 9, 1976

239,087

GABLE TOP PACKAGING CONTAINER OR THE LIKE

Ernest L. Smith, Kansas City, Mo., assignor to Phillips Petroleum Company, Bartlesville, Okla.

Filed Apr. 24, 1974, Ser. No. 463,546

Term of patent 14 years

Int. Cl. D9—01

U.S. Cl. D9—180

FIG. 1

FIG. 2

FIG. 3

FIG. 4

FIG. 1 is a view in perspective of a gable top packaging container or the like showing my new design;

FIG. 2 is a front elevational view thereof, the rear elevational view being the mirror image thereof;

FIG. 3 is a side elevational view thereof, the opposite side being the same; and

FIG. 4 is a top plan view thereof.

I claim:

The ornamental design for a gable top packaging container or the like, as shown and described.
